UNITED STATES PATENT OFFICE.

CHARLES WIRT, OF CHICAGO, ILLINOIS.

DESIGN FOR AN INSULATOR-BRACKET.

SPECIFICATION forming part of Design No. 21,439, dated March 29, 1892.

Application filed January 4, 1892. Serial No. 417,016. Term of patent 3 $\frac{1}{2}$ years.

To all whom it may concern:

Be it known that I, CHARLES WIRT, a citizen of the United States, residing at Chicago, in the county of Cook and State of Illinois, have invented and produced a new and original Design for Brackets for Electric Wires, of which the following is a specification.

My invention relates to designs for electric-wire brackets or brackets for supporting insulators for electric wires. It is illustrated in the accompanying drawings.

Figure 1 is a side view of the bracket. Fig. 2 is a plan view thereof.

Like parts are indicated by the same letters in both figures.

A is an arm; B, a substantially cylindrical portion at one end thereof; D, a plate at the other end thereof; F, a curved portion be-

tween the plate and the arm, and G G flanges on top and bottom of the arm and curved portion and extending from the cylindrical part to the plate.

I claim—

A design for an insulator-bracket, consisting of an insulator-support substantially cylindrical, a flat outwardly-curved arm thereon, a flat plate on the end of the arm, parallel to the face of the cylindrical portion, and plates or flanges parallel to each other and above and below the arm, extending from the cylindrical portion to the flat plate, substantially as shown and described.

CHARLES WIRT.

In presence of—

FRANCIS W. PARKER,
VIRGINIA WILLEY.
